FLUID CONTROL

George F. Fenno, Swarthmore, Pa.

Application September 20, 1940, Serial No. 357,605

17 Claims. (Cl. 122—451)

The proportioning of the feed water input to a boiler to the rate of steam outflow and also readjustment of the input to maintain a predetermined level of the water is disclosed in my Patent No. 1,649,342 granted November 15, 1927, and the present invention is an improvement on the means and apparatus disclosed in my previous patent. In the previous patent the various flows and level were translated into electrical impulses and these impulses were arranged as a Wheatstone bridge to effect the control means. I have found that much more accurate control can be secured by eliminating the intermediate means and using the fluids themselves to establish the analogue of a Wheatstone bridge but superior in operation.

This invention comprises a fluid control system using a divided circuit branching from a point or points of equal pressure and converging to a point or points of lower equal pressure and in which the pressure at some selected point in one branch is initially and manually set equal to the pressure of a selected point in the other branch and utilizing any deviation from this balance due to flow in the respective branches to position a flow control means to re-establish the balance, and means for adapting this control whereby it can co-act with one or more additional primary controls.

In application to an automatic feed water regulator for steam boilers including a diaphragm controlled inlet valve and in which water input balances the steam output, the invention generally stated consists in a water feed and steam offtake pipe, divergent and convergent branches interposed in the feed pipe and constituting a parallel connection, conduits from points in the respective branches to the respective sides of the diaphragm, the pressure at said points being normally balanced by the flow resistance of the respective branches, a boiler interposed at one of said points in one of said branches and from which steam is drawn in varying quantity thereby unbalancing the pressure between said points and on opposite sides of the diaphragm and operating the feed water valve in consonance with the steam output, the rate of flow of water through the other branch being changed, thereby changing the pressure on the other side of the diaphragm and restoring the balance, with or without a water level responsive device and connections modifying the action of the diaphragm valve.

The invention also comprises the improvements to be presently described and finally claimed.

In the following description reference will be made to the accompanying drawings forming part hereof and in which:

5 Figure 1 is a diagrammatic view illustrating the construction and operation of features of the invention.

Figure 2 is a similar view illustrating the application of the invention to a steam boiler.

Figure 2A is a modification of a detail.

10 Figure 3 is a view illustrating a modification, and

15 Figures 4 and 5 are views illustrating other modifications.

In the drawings 1 is the drum of a steam generator with the fluid level at elevation 2. The fluid supply enters through the pipe 3, flows through control valve 4, shown as of the well known pilot valve and piston relay operating type, then through an economizer 5 into the boiler 20 where after passing through the boiler tubes (not shown) the steam is released in a drum. The steam then passes out through super-heater 6 into the pipe 7 where it is distributed for use. At some point on the down stream side of control valve 4 some of the water is tapped off, passing through strainer 9, through line 10 containing adjusting valves 11 and 12, entering the steam line at point 13. Line 10 is usually very small pipe, passes only a small amount of water and most of the drop in pressure from point 8 to 13 is taken care of by the resistance of the pipe itself.

25 In case it is found objectionable to introduce the water directly into steam pipe 7, pipe 10 can discharge into a supplemental chamber 14, connected directly to pipe 7 and having the same pressure. The water from chamber 14 is discharged by trap 15, preferably of the continuous discharge orifice type through pipe 16. From a

30 point 32 in line 10 between the valves 11 and 12 I take off another pipe 17 which applies pressure to one side of a diaphragm 18, which on the other side has drum pressure applied by means of the reservoir 19 which always maintains a constant head of fluid, in the pipe 20. Adjustable spring 57 corrects for static head on the two sides of diaphragm 18. Any difference in pressure on the two sides of diaphragm 18 causes it to move and by means of rods and levers 21 imparts

35 movement to the pilot valve 24 which admits fluid pressure from a supplementary source through inlet 28 into cylinder 25 which contains a piston connected to valve stem 26 moving valve plunger 27 so as to adjust the flow of fluid from pipe 3. The operating fluid from the pilot valve

and power cylinder is discharged through connection 29.

The operation of the apparatus is further illustrated in Fig. 1 in which the various fluid circuits are laid out as in an electrical Wheatstone bridge, the various parts corresponding to the actual apparatus as shown in Fig. 2. Valves 11 and 12 are so adjusted that the pressure at the point 32 equals the pressure in the drum 1. If the steam output of the boiler increases, there will be an increased drop in the fluid pressure through superheater 6, but inasmuch as it is customary to maintain the pressure in steam line 7 constant, this means that the pressure in the drum 1 will be increased, because increase in steam output necessitates increase in the rate of combustion in the furnace brought about either manually or automatically (according to common practice and which forms no part of this invention) with consequent increase in steam pressure in the drum.

The increase in drum pressure immediately unbalances the pressure on diaphragm 18, starting the valve 4 to open, raising the pressure at point 8 and also at point 32 until valve 4 is opened sufficiently to raise the pressure at point 32 to equal the new pressure in the boiler drum. When this occurs the diaphragm 18 will return to its neutral position, causing the pilot valve 24 to be at neutral, which means that it is neither admitting nor discharging the auxiliary operating fluid from either side of the power piston and plunger 27 will stop at a new position so that the pressure at 8 will then be such that the pressure drop through the four legs of the fluid Wheatstone bridge will be in the same proportion under the new conditions than they were under the previous conditions, which means that the flow of water through economizer 5 will, under the new conditions, bear the same proportion to the flow of steam through superheater 6 as they were under the first set of conditions, and therefore the flow through 5 will always be proportional to the flow through 6; in other words the water input will equal the steam output.

The supply line 28 and discharge line 29 are provided with throttle valves so that the admittance and discharge of operating fluid to the power cylinder 25, which has considerable volumetric capacity, can be controlled so that the rate of movement of the main control valve 27 can be made slow enough giving time for the pressure at points 8 and 32 to change before the plunger 27 makes a full stroke, thus preventing hunting.

The pressure at the point 8 includes the static head of the boiler water-level, thus any variation from the normal level will tend to correct itself. For instance, referring to Figs. 1 and 2 a decrease in steam output always means lower pressure in drum 1 in reference to point 32; therefore, the apparatus is arranged so that when diaphragm 18 has lower pressure on the under side it tends to close feed control valve 4, but if the water level in the drum is above normal the pressure at point 8 and therefore point 32 is higher, it also moves diaphragm 18 downward tending to close valve 4, which is what is required to re-establish normal water level.

On steam generators which are not provided with economizers or super-heaters an equivalent resistance can be introduced into the water-inlet line or the steam outlet line by means of an orifice or valve in the respective lines.

If valves 11 and 12 are so adjusted that the

frictional resistance from 32 to 13 is made slightly less than through super-heater 6 and the frictional resistance from 8 to 32 is slightly more than the frictional resistance through economizer 5, the pressure at point 32 is lowered relative to the pressure in the drum 1 and diaphragm 18 will so move control valve 4 that it will slightly overfeed until a higher level of water in drum 1 raises pressure at point 32 again to bring diaphragm 18 back to neutral.

As the drop in pressure through both branches varies as the square of the flow, if valves 11 and 12 are biased as described in the preceding paragraph, the flow will tend to reduce the pressure at point 32 relative to 1 as the load increases and a still higher water level in drum 1 will be required to restore the pressure at 32, either by the static head or the co-acting level responsive means, thus giving a higher level at high ratings and a lower level at low ratings, or if point 32 is biased in the opposite direction a reverse characteristic of lower level at high ratings and a higher level at low rating can be secured. This flexibility is very desirable as some boilers operate better with the first characteristic and some better with the second.

On boilers where the pressure drop through the economizer and super-heater are high the static head due to changes in water level is sometimes not of sufficient magnitude to give adequate correction as described above and a more powerful and positive level responsive device such as thermostat 33 in Fig. 2 is required in which the movement of lever 34 moves in consonance with water level. Thermostat 33 per se forms no part of this invention and any of the other well known level responsive devices could be substituted therefor. Strut 40 which can be connected to any of the holes in lever 34 to vary the sensitivity, is connected to lever 35 pivoted at point 36, and by means of rod 37 is connected to valves 11 and 12 in such a manner that its movement closes one valve and opens the other. Turn-buckles provide for relative adjustment of valves 11 and 12. Fulcrum 36 is attached to the end of adjusting screw passing through a fixed block, and is provided with hand wheel 53 which permits of biasing point 32 as described above, and also for manually controlling valve 4 for quick filling of boiler or for securing a quick change in water level.

Under automatic control the movement of lever 34 and consequently valves 11 and 12 biases point 32 and causes either overfeeding or underfeeding as the case may require until the water level is restored to normal when lever 34 then restores valves 11 and 12 to normal setting.

There is usually some rhythmic surging of the water level in a boiler which does not affect the average level and it is not always advisable to have the level corrective element respond to these small increments. The diaphragm 18 by keeping water flow equal to steam flow will usually maintain the level sufficiently accurate and action of water level responsive element need not be applied until water level changes beyond some predetermined limits. For this method of operation, instead of connecting rod 40 directly to lever 35 it can pass through a hole in said lever and adjustable collars attached to rod 40, allowing some movement of lever 40 before influencing setting of valves 11 and 12 (Fig. 2A).

Pressure gauge 55 shows pressure at point 32 and gauge 56 shows drum pressure. These two pressure gauges are useful for securing any de-

gree of bias or for restoring valves 11 and 12 to normal position after using manual control wheel 53. As pipes 10 and 17 are very small they can be brought down to some convenient point as the main panel board where all adjustments can be readily made as hand wheel 53 and gauges 55 and 56 would be approximately at the same location. Supplementary valves can be placed in series or parallel with 11 and 12 permitting of adjustment from more than one location.

With zero boiler output, pressure at points 8, 13 and 32 would be the same, except for difference in static head, therefore movement of valves 11 and 12 as shown in Fig. 2 would not change the pressure relations; however the arrangements shown in Figs. 4 and 5 will insure water level response of the control valve at all ratings from zero to maximum.

In Fig. 4 strut 40' is not connected to valves 11 and 12 but passes through a hole in lever 21' and has a spring vertically adjustably attached to strut 40' at point 42 and can bear on the upper side of lever 21'. Also a spring is attached to strut 40' at point 44 and can bear against lever 21' from below. Space between the springs may be provided to allow a certain amount of movement of lever 21' before it contacts the springs. If the water level is too low, the tube in thermostat 33 will expand and weight 45 will pull lever 34 and strut 40' downward causing the upper spring to put pressure on top of lever 21' in proportion to the amount of deviation of level from normal. This would tend to move diaphragm 18 upward causing valve 4 to open more until the water flow increases the pressure at points 8 and 32 sufficiently to apply enough pressure through connection 17 to top of diaphragm 18, to restore pilot valve 24 to neutral position, leaving valve 4 in a more open position, however, as soon as water level is restored to normal by this over-feeding, thermostat 33 will relieve the pressure on springs 41 allowing diaphragm 18 to operate on normal balanced flow control.

The arrangement in Fig. 5 operates the same as Fig. 4 except that thermostat 33 is replaced by a second diaphragm 46 responsive to level in drum 1. Under side of diaphragm 46 is subject to steam pressure plus a constant head by means of pipe 47 connected to reservoir 19. The upper side of diaphragm 46 is connected to near the bottom of the boiler drum 1 by pipe 48 and is subject to a variable pressure due to height of water in drum 1 and to steam pressure. By means of lever 50 and link 51 diaphragm 46 is connected through springs to lever 21. Diaphragm 46 is larger than diaphragm 18 as the variations in pressure on it due to changes in water level are much smaller than the variations in pressure across diaphragm 18. By varying the pressure on lever 21 diaphragm 46 accomplishes the same result as thermostat 33 in Fig. 4.

Water level responsive diaphragm 46 can be substituted for thermostat 33 in Fig. 2, lever 50 replacing lever 34.

In Figs. 4 and 5 valves 11 and 12 are theoretically not necessary because on referring to Fig. 1 it is evident if point 32 is so selected that the drop from 8 to 32 equals the drop through 5 and the drop from 32 to 13 equals the drop through 6 the flow ratios will be correct, but practically it is difficult to so select point 32 in pipe 10 that the above conditions exactly occur and therefore valves 11 and 12 make it possible to easily correct for any error in selection of location of point 32. Also valves 11 and 12 are valuable for bias-

ing and manual control and preferably are linked together for operation by means of hand wheel 53.

The Wheatstone bridge principle of fluid control is unique in that its successful operation does not depend on maintaining any fixed differential in pressure either between the header which supplies water through pipe 3 and the boiler drum, or across the flow control valve 4. For instance if the boiler were operating at a constant load with a given setting of valve 4 and there is an increase in pressure from the boiler feed pump at point 3, there would be an increase in pressure at point 8 and therefore at point 32, but there would be no increase in pressure at drum 1, which pressure is entirely dependent on the output of steam. Therefore under this assumed condition the diaphragm 18 would move and cause pilot valve 24 to re-position control valve 4, until the flows in 5 and 6 are again equal causing the ratio of the pressure drop

$$\frac{8 \text{ to } 1}{1 \text{ to } 13}$$

to be the same as before the change thus bringing pressure at point 32 back to pressure in 1 and the pilot would return to neutral, locking valve 4 in the new position to compensate for the change in inlet pressure. This feature is very desirable as many plants use constant speed motors for driving centrifugal boiler feed pumps, which pumps have different discharge pressures for different outputs of water. The present invention thus eliminates the many devices which are expensive and none too accurate for maintaining a fixed or a variable differential pressure between two points in the main system, and which in addition to the pressure control means require an additional control means responsive to fluid level or flow or both while this invention affords complete fluid control with the use of only one control valve.

The diaphragm 18 can of course be replaced by any pressure responsive device, such as a tilting mercury U-tube, or a submersible pressure bell, and valve 4 may be operated by a reversible electric motor controlled by contacts on lever 21, or by a diaphragm or hydraulic piston, spring-loaded controlled by fluid pressure which may be varied by the position of diaphragm 18.

It will be obvious to those skilled in the art that modifications may be made in details of construction and in matters of mere form without departing from the spirit of the invention.

I claim:

1. An automatic feed water regulator for steam boilers comprising the combination of a boiler, a feed water inlet, a steam outlet, branches divergent from the inlet and then convergent to the outlet and constituting a parallel connection of which one branch is adapted to vary the pressure drop relation of the branches in response to flow through it governed by valve movement, and of which the other branch includes the boiler and is adapted to vary the pressure drop relation of the branches in response to steam flow through a part of said other branch due to steam outflow from the boiler and pressure responsive apparatus directly connected across said branches and responsive to the balance and unbalance of the pressure drop relation in the branches and connected to control the position of the valve.
2. An automatic feed water regulator for steam boilers substantially as described in claim 1 in combination with means responsive to boiler wa-

ter level and which modify the response of the pressure responsive apparatus.

3. An automatic feed water regulator for steam boilers substantially as described in claim 1, in combination with means responsive to boiler water level and including lost motion mechanism and which modifies the response of the pressure apparatus above and below predetermined limits.

4. An automatic feed water regulator for steam boilers substantially as described in claim 1, linkage interposed between the pressure responsive device and the feed water valve, a thermostatic water level device and connections from the water level device to the linkage for modifying the action of the pressure device.

5. An automatic feed water regulator for steam boilers comprising the combination of a boiler, a feed water valve having a pilot valve and piston relay for operating it, a feed water inlet, a steam outlet, branches divergent from the inlet and then convergent to the outlet and constituting a parallel connection of which one branch is adapted to vary the pressure drop relation of the branches in response to flow through it governed by feed water valve movement and of which the other branch includes the boiler and is adapted to vary the pressure drop relation of the branches in response to steam flow through a part of said other branch due to boiler demand, pressure responsive apparatus directly connected across said branches and responsive to the balance and unbalance of the pressure drop relation in the branches and connected to the pilot valve to control the position of the feed water valve.

6. An automatic feed water regulator for steam boilers comprising the combination of a boiler, a feed water valve having a pilot valve and piston relay for operating it, a feed water inlet, a steam outlet, branches divergent from the inlet and then convergent to the outlet and constituting a parallel connection of which one branch is adapted to vary the pressure drop relation of the branches in response to flow through it governed by feed water valve movement and of which the other branch includes the boiler and is adapted to vary the pressure drop relation of the branches in response to steam flow through a part of said other branch due to boiler demand, pressure responsive apparatus directly connected across said branches and responsive to the balance and unbalance of the pressure drop relation in the branches and connected to the pilot valve to control the position of the feed water valve, and means responsive to boiler water level and which modify the response of the pressure responsive apparatus.

7. An automatic feed water regulator for steam boilers including a diaphragm controlled inlet valve and a steam offtake pipe, branches divergent from the inlet valve and then convergent to the offtake pipe and constituting a parallel connection between the outlet side of the valve and the steam pipe, a boiler interposed in one of said branches and having a connection to one side of the diaphragm of the valve, a connection interposed in the other branch to the opposite side of the diaphragm, there being interposed in the last mentioned branch flow control valves, said construction providing two legs in each branch, the normal flow in each branch providing substantially the same pressure drop at the junctions of the respective legs, a change in flow in the leg connecting the boiler to the steam pipe unbalancing the pressure on the faces of the diaphragm, and actuating said valve which there-

after changes the rate of flow in another leg and balances the pressure at the other side of the diaphragm thereby making the water input balance the steam output.

8. A flow control system comprising branches connected at the same point of common inlet and at the same point of common outlet, means for supplying liquid to said point of common inlet, flow controlled means located in one of said branches by which the initial pressure at some selected point in this first branch is manually set either above or below the pressure established at a selected point in the other or second branch at a point where the liquid is changed to a gas, flow controlling means located at the common inlet to the branches and positioned by bringing these two points into balance which causes the flow on the inlet side of the second branch to become progressively higher or lower than the flow on the outlet side of the second branch, and an additional primary control responsive to the level of the liquid which is changed to gas and means for connecting said additional primary control to the flow controlling means for the first branch thereby varying said ratio.

9. A flow control system comprising the combination of a fluid bridge operating on the Wheatstone principle, a liquid flow control means operatively connected to the bridge and located at the entrance of its branches, one or more valves located in a branch of the fluid bridge for establishing pressure relations in the bridge, a vapor generating means located in the other branch of the bridge which unbalances the bridge, and means responsive to the balance i. e., equal pressure at selected points in each branch; and unbalance i. e., unequal pressure in the branches at said selected points, of the bridge due to flow, said last named means positioning the flow control means.

10. An automatic feed water regulator for steam boilers comprising the combination of a feed water valve, a fluid bridge operating on the Wheatstone principle, one leg of which includes means for changing a liquid to a gas thereby unbalancing the bridge, i. e., causing unequal pressure in the branches of the bridge, means actuated by the fluid in the bridge and responsive to the balance i. e., equal pressure at selected points in each branch, and unbalance i. e., unequal pressure in the branches at said selected points, of the bridge and controlling the position of said valve which supplies liquid to the Wheatstone bridge.

11. An automatic feed water regulator for steam boilers comprising the combination of a boiler, a feed water valve for the boiler, a fluid bridge operating on the Wheatstone principle, means actuated by the fluid in the bridge and responsive to the balance i. e. equal pressure at selected points in each branch, and unbalance i. e. unequal pressure in the branches at said selected points, of the bridge and controlling the position of said valve, and devices responsive to boiler water level and which modify the action of said means in respect to the positioning of said valve, said boiler located in part of the bridge, and said valve located at the entrance of the bridge.

12. In an automatic feed water regulator for steam boilers the combination of a boiler, a feed water valve, a fluid bridge operating on the Wheatstone principle and through a part of one leg of which steam passes from the boiler, and apparatus actuated by the fluid in the bridge

75

and responsive to changes in balance of the bridge, i. e. the changes in the differential pressure in the branches of the bridge, and connections between said apparatus and feed water valve positioning said valve for automatically maintaining a fixed ratio between water input and steam output, said boiler located in part of the bridge, said valve located at the entrance of the bridge.

13. In an automatic feed water regulator for steam boilers the combination of a boiler, a feed water valve, a fluid bridge operating on the Wheatstone principle of which one leg includes the boiler and through a part of which leg steam passes, apparatus actuated by the fluid in the bridge and responsive to changes in balance of the bridge, i. e., deviation from equal pressure at selected points in the respective branches, for automatically maintaining a fixed ratio between water input and steam output, said apparatus operatively related to said feed water valve, said feed water valve located at the inlet to the branches of said bridge, and a boiler water level regulator responsive to changes in water level, a connection between the water level regulator and the feed water valve which positions the latter thereby modifying the relative values of the pressures at the selected points.

14. A flow control system comprising a water inlet, a steam outlet, branches divergent from the inlet and then convergent to the outlet and in which the pressure at some selected point on one branch is set by flow control in that branch equal to the pressure established at a selected point in the other branch of the circuit by flow variation, a steam generator in said other branch, and flow control means at the inlet of the branches and positioned by apparatus arranged to be responsive to any deviation from the equality of pressures in said branches due to change in flow, said last named means and apparatus operated to re-establish the equality of pressures in said branches.

15. A flow control system comprising a water inlet, a steam outlet, branches divergent from the inlet and then convergent to the outlet and in which the pressure at some selected point on one branch is set by flow control in that branch equal

to the pressure established at a selected point in the other branch of the circuit by flow variation, a steam generator in said other branch, flow control means at the inlet to the divergent branches and positioned by any deviation from the balance due to change in flow to tend to re-establish the balance, and an additional primary control responsive to liquid level in said steam generator, a connection between the additional primary control and the flow control means which positions the latter thereby modifying the action of said flow control means.

16. A flow control system comprising the combination of, a fluid bridge operating on the Wheatstone principle, a liquid flow control means operatively connected to the inlet to the bridge, one branch of the fluid bridge proportioned for establishing the pressure relations in the bridge, a vapor generating means located in the other branch which unbalances the bridge, and means responsive to the balance, i. e., equal pressure at selected points in each branch, and unbalance, i. e. unequal pressure in the branches at said selected points of the bridge due to flow, which positions the flow control means.

17. A flow control system comprising, branches connected at the same point of common inlet and at the same point of common outlet, liquid flow control means in the first of said branches by which the initial pressure at some selected point is manually set less than the pressure established at a selected point in the second branch at which the liquid is changed to a gas, flow controlling means located at the common inlet to the branches, means for positioning the last-mentioned control means by the difference in pressure between the selected points, and a regulator responsive to fluid level at the point where the liquid is changed to a gas having lost motion connection for modifying the pressure at the selected point in the first branch which causes the flow, i. e., weight per unit of time, on the inlet side of the second branch to become greater than the flow, i. e., weight per unit of time, on the outlet side of the branch.
